UNITED STATES PATENT OFFICE.

IVER K. IVERSEN, OF MARLETTE, MICHIGAN.

SPECIAL FORM OF ATTACHMENT FOR BUCKETS AND THE LIKE.

1,179,725.

Specification of Letters Patent. Patented Apr. 18, 1916.

Application filed October 3, 1914. Serial No. 864,800.

To all whom it may concern:

Be it known that I, IVER K. IVERSEN, a citizen of Germany, residing at Marlette, in the county of Sanilac and state of Michigan, have invented certain new and useful Improvements in Special Forms of Attachment for Buckets and the like; and I do hereby declare the following to be a full, clear, and exact description of the invention, such as will enable others skilled in the art to which it appertains to make and use the same.

My invention relates to an attachment for buckets or pails designed to maintain in an upright position, a vessel suspended in water within said bucket.

My object is to supply a cheap and effective appliance to cool liquids and especially to remove the animal heat from cream to retard the souring thereof.

In the accompanying drawings herewith, which are made a part of this application, Figure 1 is a perspective view of the upper portion of a pail containing one of my coolers. Fig. 2 is a vertical cross section of the upper end of the cooler on the line 2—2 of Fig. 1. Fig. 3 shows a section of the yoke, with the bayonet slot therein.

An ordinary pail 3 is provided with ears 30 4, having bayonet slots 5 therein, the said ears are fastened by rivets adjacent the edge of the said pail at points diametrically opposite each other, with that part of the ear containing the said slot projecting above the rim of the said pail.

A yoke comprising two metal bars 6 and 7, bent in their central part into a half circle and the ends extended laterally and riveted together so that the two half circles 40 will form a true circle the riveted ends extending to and slightly beyond the rim of the pail when they are positioned thereon, the extremities of the extended ends are fashioned to enter and snugly fit the said 45 slots 5 in the said ears. On diametrically opposite sides of the circle thus formed half way between the two extended ends and in the lower edge of the bars, are formed two bayonet slots 8 and 9 which engage projecting studs secured to the cooler as will be 50 more fully described later.

The cooler 10 comprises a container of

smaller diameter and less depth than the pail 3. The upper edge 11 thereof is turned outwardly and downwardly forming a depending lip or annular flange 12 which is designed to prevent the drip of water from the cooler when it is being emptied of its contents the said flange catching and retaining any moisture that may adhere to the sides of the cooler when it is lifted from the pail and reversed in its position by the act of emptying the contents thereof. Upon the flange 12 are secured two studs 13 and 14 adapted to engage the slots 8 and 9 for the purpose of securing the cooler 10 within the said yoke to prevent the cooler from floating upon the water in the pail 3 when the said cooler is wholly or partially empty. A lid 15 is provided to be used in connection with the cooler as may be desired.

In operation the cooler is positioned in the pail by first securing the yoke to the cooler by inserting the studs 13 and 14 in the slots 8 and 9 and then giving the yoke 75 a slight turn which engages the studs in the horizontal part of its slots. The cooler is then attached to the pail by means of the slots 5 and the laterally extended arms of the yoke in a similar manner to that by 80 which the yoke was attached to the cooler. The cooler is thus suspended within the pail without touching either sides or bottom. Water is poured into the pail until it approaches the top thereof, the top of the 85 cooler being elevated sufficiently above the top of the pail by the yoke to prevent the water from entering the cooler which is now ready to receive the cream as it is collected and the cooling proceeds simultaneously 90 with the gathering of the cream.

Believing that the construction, advantages and manner of using my invention have thus been made clearly apparent, further description is deemed unnecessary.

Having thus fully described my invention what I desire to secure by Letters Patent is:—

In combination with a pail having ears attached thereto provided with bayonet 100 slots, of a cooler of less diameter than said pail having a depending annular lip, studs secured to said lip, and a yoke having a central circular body portion provided with

bayonet slots in its lower edge and laterally extending arms, the ends of said arms engaging the slots in said ears, the studs of said cooler engaging the slots in said circular body portion, whereby said cooler is held in upright position within said pail.

In testimony whereof I have signed my

name to this specification in the presence of two subscribing witnesses.

IVER K. IVERSEN.
